UNITED STATES PATENT OFFICE.

DAVID C. IMBODEN, OF KANSAS CITY, MISSOURI.

DESIGN FOR LETTERS.

SPECIFICATION forming part of Design No. 11,651, dated February 10, 1880.

Application filed December 26, 1879. Term of patent 14 years.

To all whom it may concern:

Be it known that I, DAVID C. IMBODEN, of Kansas City, Missouri, have invented a new and original Design for Letters and Figures, 5 of which the following is a specification.

The letters and figures designed in accordance with my invention are made up of representations of cereals. Into the composition of each letter enters an ear of corn partially 10 closed in its husk, and the remainder of the letter is made up of properly-grouped clusters or bunches of the smaller cereals, such as wheat, oats, rye, and barley.

In illustration of my design I have shown 15 in the accompanying drawing a number of letters thus made up, which are put together to form the word "Grain." Each letter, as will be seen by examination of the drawing, is composed of the representation of an ear of corn 20 partially inclosed in its husk, and which preferably occupies an upright, or nearly an upright, position in the letter, while the remain-

der of the letter is formed of representations of the smaller cereals, such as wheat or others hereinbefore mentioned, using, preferably, the heads, for the most part, although the stalks or straw as well may enter into the composition of the letter. 25

The letters represented sufficiently indicate the way in which the design may be carried 30 out throughout the entire alphabet. It is manifest, also, that the same design may be used in the composition of figures or numerals.

What I claim, and desire to secure by Letters Patent, is—

The design for letters and figures herein described and shown.

In testimony whereof I have hereunto signed my name this 20th day of December, A. D. 1879.

DAVID C. IMBODEN.
